UNITED STATES PATENT OFFICE.

ALBERT L. MORTON, OF SPRINGFIELD, ILLINOIS.

DESIGN FOR A TOILET-CHAIR.

59,126.

Specification for Design.

Patented Sept. 20, 1921.

Application filed January 28, 1921. Serial No. 440,817. Term of patent 14 years.

To all whom it may concern:

Be it known that I, ALBERT L. MORTON, a citizen of the United States, residing at Springfield, in the county of Sangamon and State of Illinois, have invented a new, original, and ornamental Design for Toilet-Chairs, of which the following is a specification, reference being had to the accompanying drawing, forming part thereof.

The figure is a perspective view of a toilet chair showing my new design.

Distinctive features of the design are: the graceful contour of the back of the chair; and the ornamental configuration of the feet of the chair.

I claim:

The ornamental design for a toilet chair as shown.

ALBERT L. MORTON.
